UNITED STATES PATENT OFFICE.

JOSEPH WAY, JR., OF PHILADELPHIA, PENNSYLVANIA.

RECEPTACLE AND BAG.

1,190,492.

Specification of Letters Patent. Patented July 11, 1916.

Application filed February 2, 1916. Serial No. 75,803.

To all whom it may concern:

Be it known that I, JOSEPH WAY, Jr., a citizen of the United States, residing at Philadelphia, in the county of Philadelphia 5 and State of Pennsylvania, have invented new and useful Improvements in Receptacles and Bags, of which the following is a specification.

This invention relates to improvements in 10 paper bags and analogous receptacles, and has for an object to provide a receptacle or carrier capable of being readily and conveniently carried.

The invention relates more particularly 15 to the usual merchandise containing paper bag and which, adjacent the open end thereof, is provided with a plurality of reinforced hand receiving openings, the latter being adapted to form a hand hold, when 20 the bag is being carried, and furthermore effectively close the open end of the bag to prevent the commodities confined therein from accidental removal or from becoming contaminated with dust or dirt.

25 With these and other ends in view which will readily appear as the nature of the invention is better understood, the same consists in the improved construction and novel arrangement and combination of parts 30 which will be hereinafter fully described and particularly pointed out in the claims.

In the accompanying drawings there has 35 been illustrated a simple and preferred form of the invention, it being, however, understood that no limitation is necessarily made to the precise structural details therein exhibited, but that changes alterations and modifications within the scope of the claims may be resorted to when desired.

40 In the drawing:—Figure 1 is a side elevation of the bag or receptacle comprising the present invention, Fig. 2 is a similar view illustrating the bag when in a position to be carried, Fig. 3 is a transverse 45 section on the line 3—3 of Fig. 1, Fig. 4 is a similar view on the line 4—4 of Fig. 2, and Fig. 5 is a detail view illustrating a slightly modified method of reinforcing the hand receiving openings.

50 Similar characters of reference denote like parts throughout all of the views of the drawing.

Referring more particularly to the draw-

ings there is shown an ordinary form of merchandise receiving bag 1, provided with 55 the usual closed end 2 and an entrance or open extremity 3. In order to facilitate the operation of carrying the bag, the latter is preferably provided, adjacent the extremity 3, with vertically spaced elongated openings 60 4 and by which the bag will be readily supported in a simple method to be presently disclosed. After the bag 1 has been filled and is ready to be carried, the extremity 3 is folded on a line, located between the 65 slots or openings 4 and indicated as at 5 by dotted lines in Fig. 1, until said extremity 3 is positioned against the body of the bag. This action results in alining for 70 registering the openings 4 and in simultaneously closing the entrance extremity of said bag so as to prevent commodities positioned therein from becoming accidentally lost. By passing the hand through the alining 75 openings the bag can be readily grasped so as to be conveniently carried, and when so carried said bag will be effectively sealed, eliminating the use of cord, twine or other securing elements.

When said bag is formed of relatively 80 thin paper or similar material, practice has disclosed that it is necessary for one or more of the openings 4 to be reinforced by some suitable means, so that, when the bag is carried, the weight of the material therein 85 will not be of sufficient strength to tear the bag around the opening so as to destroy the utility of the latter. The reinforcing means, acts in the capacity of a hand grip, enabling the carrier of the bag to obtain a better 90 hold thereon, and moreover, greatly prolongs the life of said bag.

The preferred form of reinforcing the 95 openings 4 has been clearly illustrated in Figs. 1 to 4 in the drawings and consists in securing to one side of the bag 1 reinforcing strips 6, which completely surround said openings 4 and are of sufficient strength to prevent the body of the bag from tearing when being carried. The strips are preferably formed of relatively heavy card board 100 and are secured to said bag by a suitable adhesive or by any other convenient means. Another method of reinforcing the openings 4 has been disclosed in Fig. 5 of the 105 drawings, wherein wire elements 7 have been

shown as secured to the body 1 in a position to surround the said hand receiving openings. The functions of the elements 7 are identical with those of the strips 6 5 and therefore need no additional description concerning their duties.

From the foregoing it will be seen that the objects of the present invention have been achieved, and all the advantageous 10 features above mentioned, are among others, present. The bag is of simple construction, of few parts, and absolutely reliable in all respects. From a commercial standpoint, the bags constructed in accordance with the 15 present invention will be far more economical to use than the ordinary form, inasmuch as the improved bags will be used a number

of times, whereas ordinary bags are generally destroyed after a single usage.

I claim:—

A bag of the class described embodying a commodity receiving body having a normally open end and formed adjacent said end with a pair of vertically spaced hand receiving openings, the marginal portion of 25 said body being bent downwardly at a point between said openings and brought to bear against the body portion for registering said openings with one another, and a reinforcing member surrounding each of said 30 openings and serving as a hand grip.

In testimony whereof I affix my signature.

JOSEPH WAY, JR.
